Specification of Letters Patent. Patented Oct. 30, 1917.

Application filed April 4, 1914. Serial No. 829,412.

To all whom it may concern:

Be it known that I, MILLARD L. JOHNSTON, a citizen of the United States, residing at Utica, in the county of Oneida and 5 State of New York, have invented certain new and useful Improvements in Clutches, of which the following is a specification, reference being had therein to the accompanying drawing.

10 My invention relates to a clutch and I declare the following to be a full, concise, and exact description thereof sufficient to enable anyone skilled in the art to which it appertains to make and use the same, reference 15 being had to the accompanying drawings in which like reference characters refer to like parts throughout the specification.

The object of the invention is to provide a simple, efficient clutch adapted more particularly for use in connection with the platen roller of a typewriter. The clutch is so constructed that by the mere manipulation of a handle, the ratchet wheel will be automatically released, whereby the platen 25 roller may be free to turn in either direction for the convenience of the typewriter operator.

I attain these objects by the mechanism disclosed in the following drawings in 30 which:

Figure 1 is a side elevation of the clutch, showing the same assembled to a platen roller in section;

Fig. 2 is an enlarged vertical section of 35 the clutch and shaft of the platen roller;

Fig. 3 is a detail perspective view of a thimble employed;

Fig. 4 is a detail perspective view of the head of a plunger employed;

40 Fig. 5 is an enlarged plan view of the clutch, looking in the direction of the arrow, and showing a section taken on the line 5-5 of Fig. 2;

Fig. 6 is a fragmentary detail view in section, showing certain holes in the head of a plunger employed.

Referring more particularly to the drawings, the clutch is assembled to one end of a shaft —1— passing through the center of 50 the platen roller 2 adapted to revolve therewith. The end of the shaft —1— is recessed at 3 for the disposition of the coiled spring 4, that normally presses against the head 5 of the plunger having an extension 6 to which is secured by a set screw 7 a handle 8. The end of the recess 3 is closed by

a plug 9, screw threaded interiorly to the recess 3 and having an aperture for the passage of the extension 6 of the plunger. The roller 2 is recessed at 10 for the housing of 60 the member 11 of the clutch casing. The member 11 has a loose bearing at 12 on the shaft —1— and is threaded at 13 for the mounting of the ratchet member 14. There is also a member 15 having a loose bearing 65 upon the shaft —1— at 16 and upon the extension 6 at 17, and is likewise screw threaded at 18 for the mounting of the ratchet 14. The members 11 and 15 are assembled to the ratchet 14, in such a manner that there is 70 formed a circumferential recess 19, adapted for the reception of the ends 20 of the dogs 21, whose opposite ends 22 are loosely held in the holes 23 formed in the head 5 of the plunger. The member 11 is prevented from 75 sliding off the end of the shaft —1— by the thimble 24, which abuts at one end against the inner surface of the member 11 and at its opposite end against the circumferential shoulder 25 formed by the cutting or milling 80 of the end of the shaft —1—. The thimble 24 is provided with orifices 26 corresponding in size to the orifices 27 formed in the end of the shaft —1—. The orifices 26 and 27 permit the forward movement of the 85 dogs 21, when the plunger is actuated forward by the manipulation of the handle 8.

The operation of the device is effected by assembling the coiled spring 4 in the recess 3 of the shaft —1—, so as to bear or press 90 against the head 5 of the plunger, which is likewise disposed in the recess 3 and held therein by the plug 9. The members 11 and 15 are also assembled upon the shaft —1— in such a manner that they may freely rotate 95 thereon. The said members 11 and 15 are held in position on the end of the shaft —1— by the thimble 24, which is sprung into position, and by the shoulder 30 of the member 15. The dogs 21 are disposed in position with their ends 22 loosely held in the holes 23 in the head 5 and their ends 20 in the recess 19. The walls of the holes 23 are tapered or inclined as at 32, whereby to permit the dogs 21 to tip, when the ends 22 of 105 the same are moved inward, as shown in the dotted lines in Fig. 2. Furthermore, in Fig. 2, the full lines show the dogs 21 having their ends 20 engaging the members 11 and 15 at points or lines 35 and 36, whereby the 110 ratchet 14 will be actuated or rotated with the rotation of the shaft —1— and the platen

roller 2. In order to release the ratchet 14, so that the shaft —1— and the platen roller 2 will be free to move independently thereof, the operator pushes inward on the handle 8 5 to thereby move the head 5 of the plunger inward, so as to move the dogs into the plane represented by the dotted lines in Fig. 2, in which position the ends 20 of the dogs 21 will lie parallel with the sides of the recess 10 19 and be disengaged therefrom along the lines 35 and 36. Upon withdrawing the hand from the handle 8, the spring 4 will urge the head 5 of the plunger back into its normal position, as shown by full lines in 15 Fig. 2, where the ends 20 of the dogs 21 will again engage the members 11 and 15 and throw the ratchet into actuation with the shaft —1— and the platen roller 2. The ends 22 of the dogs 21 are rounded off at 20 40 to minimize the surface of the ends 20 of the dogs 21 for contact with the sides of the recess 19.

Having thus described my invention what I claim as new and desire to secure by Letters Patent is:

1. In a clutch a ratchet wheel, dogs, having their free ends rounded off, whereby to minimize the surface of contact, for engaging said ratchet wheel, whereby said wheel 30 will be rotated, and a plunger for releasing said dogs from engaging with said ratchet wheel.
2. In a clutch for typewriters, a ratchet wheel, a casing assembled to a shaft, a thimble for holding said casing in assembled position on said shaft, dogs loosely mounted in said casing and having their free ends rounded off, whereby to minimize the surface of contact, means whereby said dogs 40 will engage said casing, whereby said ratchet wheel will turn with said shaft, and a plunger for releasing said dogs from engagement with said casing, whereby said ratchet wheel will turn independently of said shaft.
- 45 3. In a clutch member for typewriters, a platen adapted to revolve with a shaft, a recess in the end of said shaft, a casing loosely mounted adjacent the end of said shaft, a thimble for holding said casing in assembled 50 position on said shaft, a ratchet mounted

upon said casing, a plunger adapted to slide in the recess in said shaft, dogs mounted in said plunger and adapted to engage said casing, whereby said ratchet will revolve with said platen and shaft, means for normally holding said dogs in engagement with said casing, and means for releasing said dogs from engaging said casing, whereby said ratchet may be turned independently of said platen.

4. In a clutch for typewriters, a platen adapted to revolve with a shaft, a recess in the end of said shaft, a casing loosely mounted upon said shaft, said casing comprising two members screw mounted to a ratchet, a recess formed by the assembling of said members to said ratchet, a plunger mounted to slide in the recess in said shaft, dogs mounted in said plunger, said dogs adapted to engage the sides of said recess formed by the members of said casing, whereby said ratchet will revolve with said platen, and means for releasing said dogs from engagement with the recess formed by said members, whereby said platen may be turned independently of said ratchet.

5. In a clutch for typewriters, a shaft supporting a platen adapted to revolve therewith, a recess in the end of said shaft, a casing loosely mounted upon the end of said shaft, a thimble, whereby to aid in holding said casing upon said shaft, a shoulder formed in the end of said shaft, whereby to aid in holding said thimble in assembled position, a plunger mounted in the recess in the end of the shaft, dogs mounted in said plunger, a spring for holding said dogs normally in engagement with said casing, whereby said ratchet will revolve with said platen, and means for pushing said plunger 90 against the tension of said spring, whereby said dogs will be released from engagement with said casing to permit the platen to turn independently of said ratchet.

In testimony whereof I have affixed my 95 signature in the presence of two witnesses.

MILLARD L. JOHNSTON.
